US00D547640S

(12) **United States Design Patent** (10) **Patent No.:** **US D547,640 S**
Remmers (45) **Date of Patent:** **** Jul. 31, 2007**

(54) **DRAWER BRACKET**

(75) Inventor: **Lee E. Remmers**, Ocala, FL (US)

AT 260460 3/1968

(73) Assignee: **Clairson, Inc.**, Newark, DE (US)

(Continued)

(**) Term: **14 Years**

(21) Appl. No.: **29/244,571**

(22) Filed: **Dec. 12, 2005**

Related U.S. Application Data

(63) Continuation-in-part of application No. 10/424,681, filed on Apr. 28, 2003, now Pat. No. 7,021,730.

(51) **LOC (8) Cl.** **08-05**

(52) **U.S. Cl.** **D8/381**

(58) **Field of Classification Search** D8/381, D8/380, 373, 349, 402, 308; D6/574, 572, D6/556, 449, 511, 478, 492, 367, 509, 491; 248/300, 298.1, 250, 247, 243, 236, 235, 248/222.21-61, 225.11, 214, 208, 301, 297.21; 108/152, 108; 312/408, 404; 229/120.07-34; 40/661.03, 642.02; 211/184; D19/34.1

(57) **CLAIM**

The ornamental design for a drawer bracket, as shown and described.

DESCRIPTION

FIG. 1 is a perspective view of the drawer bracket, showing my new design;

FIG. 2 is another perspective view of the drawer bracket shown in FIG. 1;

FIG. 3 is a side elevation view of the drawer bracket shown in FIG. 2;

FIG. 4 is a side elevation view of the drawer bracket shown in FIG. 1;

FIG. 5 is a top plan view of the drawer bracket shown in FIG. 4;

FIG. 6 is a bottom plan view of the drawer bracket shown in FIG. 4;

FIG. 7 is a front elevation view of the drawer bracket shown in FIG. 1; and,

FIG. 8 is a rear elevation view of the drawer bracket shown in FIG. 1.
